NEW YORK

FUMIGATOR

Application filed October 20, 1932. Serial No. 638,736.

Our invention relates to apparatus intended for vaporizing fumigants, deodorizers, etc., and particularly of the type of our application Serial Number 607,950 filed

5 April 28th, 1932.

The main object of our present invention is to provide a construction for efficiently vaporizing a material such as paradichlorbenzine for the purpose of exterminating 10 moths and other insects and their larvae.

Such devices must be simple in construction and easy and convenient to use. It is also important that they may be readily refilled with the vaporizable material. It is 15 further important that the device shall be capable of use in all sorts of circumstances, for instance, by merely setting the device on the floor.

It is also desirable that the device be operable electrically and that the electrical unit be readily replaceable.

It is also desirable that the heater unit be inexpensive and durable and efficient.

All of these features have been carefully 25 considered in developing the invention herein shown and described. We have accordingly provided a receptacle in the form of a metal shell of cup-like form adapted to hold the vaporizable compound.

30 The heater is in the form of a resistance wire mounted on a cross bar adapted to be supported in the upper edge of the shell close to the surface of the vaporizable compound. The heater unit is preferably detachably mounted so that it can be moved out of the way when refilling the shell. The shell is also provided with a detachable cover which fits the rim of the shell and guards the heater unit and when closed substantially prevents or minimizes evaporation.

35 This cover is also preferably provided with a valve-like shutter for controlling the emission of vapor from the device. The conductor cord leading to the heater is preferably led in through the side between the overlapping edges of the shell and cover so that the cover may be removed without disturbing the heater unit which is thus exposed for inspection and removal. In this way 45 the device may also be used for more rapid

evaporation by removing the cover entirely and thus exposing the entire upper surface of the fumigant or vaporant.

Fig. 1 is a vertical sectional view of one form of device embodying our invention. 55

Fig. 2 is a plan view with the cover removed and part of a heater unit shown in section.

Fig. 3 is a sectional view on the plane of the line 3—3 of Fig. 1. 60

Fig. 4 is a fragmentary detail showing the method of positioning the conductor.

Fig. 5 is a perspective view of a modified form of heater unit.

The shell of the device is preferably 65 formed of sheet metal consisting of the body part 7 and the cover 8 having interfitting flanges 9 and 10. The body part of the shell is adapted to contain the fumigant material or compound preferably in the form 70 of a cake 11, which cake will ordinarily fill the body up to approximately the level of the flange 9. The shell may be ribbed or corrugated externally as well as internally 75 and the cake would ordinarily be shaped to fit the shell.

The cover may have a central raised portion 12 provided with a valve-like shutter 13 which is mounted to rotate on a central rivet 14. This valve or shutter member has a 80 rim or flange 15 to facilitate rotation so as to open and close the outlet from the shell or casing.

The heater unit consists of a resistance wire 16 in the form, for instance, of a coil 85 wound on an insulating support 17, for instance, of mica and in turn supported by the cross bar 18 from which of course the resistance wire is insulated. The edges of this cross bar may be bent over in the form of 90 flanges 19 to embrace the resistance element which will of course be enclosed in suitable insulation. The conductors 20 and 21 are connected to terminals 22 and 23 carried by the cross bar but insulated from it. The entire resistance wire and the terminals are 95 preferably enclosed in insulation 24, for instance asbestos tape, so as to prevent accidental contact with live parts. The conductors 20 and 21 will of course be insulated 100

in the usual manner and may be further protected by an insulating member 25 adapted to resist the heat created by the passage of the current through the resistance wire. The conductors are preferably led into the shell through one edge and positioned in a notch 26 in the flange 9.

The cover 8 may also be similarly notched at this point to position it with respect to the heater unit and its conductor.

It will be seen that the outer end of the insulating protector 25 is flanged to assist in positioning it with respect to the edge of the shell.

15 The opposite ends of the cross bar 18 are supported in opposite sides of the shell for instance in the groove formed by the flange 9. One end of the cross bar may be hinged at 27 to the edge of the shell and the other end 28 provided with a finger adapted to frictionally engage the opposite side of the shell where it may be conveniently positioned by inwardly projecting lugs 29—29.

20 When the cover is off it will be seen that 25 the heater unit is retained in the body of the shell where it can be readily inspected. When it is desired to refill the shell the heater unit can be removed or swung up out of the way by rotating it above the hinge 27.

25 30 In case the heater unit is damaged it may be easily entirely detached by simply drawing out the hinge pin. By reason of the fact that the heater unit and the conducting cord are in no way attached to or dependent upon the presence of the cover it will be seen that the device may be readily manufactured and assembled most economically.

35 For instance, the body and cover of the shell may be made by sheet metal workers 40 and the heater unit may be made by electrical specialists and the parts readily assembled without the use of any tools and without requiring any electrical skill in wiring on the part of the assembler.

45 50 When the device is to be used it is merely necessary to turn on the current in the heater circuit and open the shutter 13 or remove the cover entirely depending upon the rate at which it is desired to carry out the fumigating operation.

55 By making the cover shallow and bringing it down close to the heater unit we are able to utilize the heat with its maximum efficiency since there is less loss by radiation.

60 In Fig. 5 we have shown a modified form of heater unit in which the cross bar 30 supports the resistance wire as above described, but the cross bar is provided with two flanges 31 and 32 at opposite ends which are adapted to rest in the groove of the shell. Preferably the cross bar and flange are so proportioned with respect to the shell that the heater unit will be frictionally held 65 in place when the cover is on. Flange 32

may be provided with an eyelet 33 to guide the conductors.

70 It will be seen from the foregoing that the invention contemplates a shell formed in two parts with a separable heater unit adapted to be supported entirely within the body of the shell.

75 While it is preferred that the heater unit shall be detachably mounted in the shell or casing so as to permit repair and replacement and so as to permit the insertion of the fumigant in solid or cake form, it should be understood that many of the advantages of the invention might be had with a fixed type of heater in case the fumigant is in a liquid or flake form.

80 As the heater unit is mounted directly in the body of the shell close to the vaporant, heat is conducted directly from the metallic cross bar of the heater unit to the metallic shell as well as by radiation to the surface of the vaporant.

85 The shallow cover serves to reflect the heat from the resistance wire so as to quickly and efficiently heat the material to be vaporized. By leading the conductors in through one edge of the shell we avoid the danger of overheating which exists when the cord is led in through the center of the top.

90 We claim:

1. A fumigator comprising two metallic cuplike members having interfitting flanges, a resistance wire heater unit detachably secured in the upper part of the lower member above the contents of the lower member, said upper member having a controlled outlet and means for clamping the conductor leads to the heater unit between the two members.

100 105 2. A fumigator comprising a shell adapted to contain a vaporizable compound, an electrical heater unit connected at one end to said shell and adapted to extend over the shell to heat the compound from above and adapted to be swung to one side to permit insertion of the compound and a cover detachably connected to the shell and adapted to control vaporization.

110 115 3. A fumigator comprising a shell adapted to contain a cake of vaporizable compound, an electric heater unit hinged to one edge of the shell and adapted to be swung into place across the cake within the shell and a cover for the shell.

120 125 4. A fumigator comprising a shell adapted to contain a vaporizable compound, an electric heater unit arranged transversely of the shell above the compound and means for positioning the opposite ends of the heater unit at the sides of the shell, and a cover removably connected to the shell independently of the heater unit.

130 5. A fumigator comprising a shell for holding a vaporant, an electric heater unit hinged to one edge thereof, a cover for the

shell and a conductor for the heater unit clamped between the shell and cover.

6. A fumigator comprising a shell for a vaporant, an electric heater unit detachably mounted in the upper edge of the shell, a cover for the shell close to the heater unit but removable independently thereof and a conductor cord leading to the heater unit and positioned in an open slot in the edge of the shell.

10 7. A fumigator comprising a shell having an inner groove, a heater unit detachably mounted in said groove, a shallow cover supported on the shell and having a controlled 15 outlet, and a conductor connected to the heater unit and clamped between the shell and cover.

8. A fumigator comprising a shell for holding a vaporant, a heater unit having a 20 cross bar detachably supported in the shell, an eyelet carried by the cross bar for the conductor cable leading to the heater unit, and a cover for the shell and heater unit.

9. A fumigator comprising a receptacle 25 for the vaporant, having grooved seats in the opposite sides, a heater unit positioned in the grooved seats, a cover for the receptacle, and conductors for the heater unit clamped between the cover and receptacle.

30 10. A fumigator comprising a receptacle, a heater unit hinged at one end to one side of the receptacle and having a lug at its other end supported in the opposite side of the receptacle, and a cover for the receptacle 35 having a controlled outlet.

11. A fumigator comprising a resilient metal shell, a heater unit detachably sprung between opposite edges of the shell, and a cover for assisting in holding the heater unit 40 in the shell.

12. A vaporizer comprising a metallic shell having a flat bottom, an electric heater unit comprising a metallic cross bar, a resistance wire carried thereby, means for supporting the ends of the cross bar in the upper edge of the shell in thermally conductive relation thereto, and a cover for the shell removable independently of the heater unit.
